United States Patent

Des. 235,746
Patented July 8, 1975

235,746

TRAFFIC HAZARD MARKER

Will Clarke England, 7310 Easterrest,
Austin, Tex. 78752

Filed Jan. 11, 1974, Ser. No. 432,637

Term of patent 14 years

Int. Cl. D10—06

U.S. Cl. D10—109

FIG. 1

FIG. 1 is a perspective view of a traffic hazard marker showing my new design;

FIG. 2 is a top plan view thereof on a reduced scale;

FIG. 3 is a bottom plan view thereof on a reduced scale;

FIG. 4 is a vertical cross-section taken on a line 4-4 of FIG. 2 on a reduced scale of FIG. 1.

I claim:

The ornamental design for a traffic hazard marker, substantially as shown and described.
